UNITED STATES PATENT OFFICE.

ARTHUR B. CLUNIES, OF ROCHESTER, NEW YORK, ASSIGNOR TO SILL
STOVE WORKS, OF SAME PLACE.

DESIGN FOR A FIRE-POT FOR STOVES.

SPECIFICATION forming part of Design No. 34,979, dated August 20, 1901.

Application filed July 15, 1901. Serial No. 68,426. Term of patent 14 years.

To all whom it may concern:

Be it known that I, ARTHUR B. CLUNIES, a citizen of the United States, and a resident of Rochester, in the county of Monroe and State of New York, have invented and produced a new and original Design for a Fire-Pot for Stoves; and I do hereby declare the following to be a full, clear, and exact description of the same, in connection with the accompanying drawings, forming a part thereof.

In the drawings, Figure 1 is a perspective view of a fire-pot constructed according to my design. Fig. 2 is a sectional view on the line $x-x$ of Fig. 1, and Fig. 3 is a similar view on the line $y-y$ of Fig. 1.

Similar reference-numerals in the three figures indicate similar parts.

The fire-pot illustrated in the accompany-

ing drawings consists of a body 1, circular in form, having the outwardly-flaring top 2, ²⁰ the edge of which overhangs or extends outwardly, being provided with a rounding surface 3, and at equidistant points upon the rim are located lugs 5, having waved or irregular surfaces 6 upon their edges, which extend ²⁵ inwardly toward the top of the lugs. Around the bottom edge of the body are provided downwardly-extending fingers 7.

I claim—

The design for a fire-pot for stoves substantially as herein shown and described.

ARTHUR B. CLUNIES.
